REFRIGERATED DISPLAY STAND

Louis F. Barroero, 1585 Daniels Drive,
San Leandro, Calif.

Filed Feb. 17, 1961, Ser. No. 63,967

Term of patent 7 years

(Cl. D80—11)

FIG. 1 is a perspective view taken from the top and to one side of a refrigerated display stand embodying my new design, the rear view thereof being substantially plain;

FIG. 2 is a side elevation thereof; and

FIG. 3 is a cross sectional view taken on line 3—3 of FIG. 1.

The dominant features of my design reside in the full-line portions of the drawings. It is to be understood that the apertures which are partially shown in broken lines cover the entire surface of each of the shelves and the inside of the canopy has a flat horizontal panel extending from the junction of the scalloped fringe in a conical section to the rear wall.

I claim:

The ornamental design for a refrigerated display stand, as shown and described.
